2 Sheets-Sheet 1

Figure 1 is a detailed electrical circuit diagram. The diagram includes several components and their connections:

- Left Side:** Features two circular components labeled 'A' and 'A' (with a prime symbol). These are connected to a vertical line labeled 'H'.
- Central Column:** A vertical line labeled 'C' is connected to the 'H' line. It also contains a series of contacts and components labeled 1 through 55, including relays, switches, and resistors.
- Right Side:** A circular component labeled 'I' is connected to the 'H' line. It is also connected to a vertical line labeled 'GEN'.
- Bottom:** A vertical line labeled '4' is connected to the 'H' line. It contains components labeled 1 through 11.
- Bottom Left:** A vertical line labeled '3' is connected to the 'H' line. It contains components labeled 1 through 14.
- Bottom Right:** A vertical line labeled '2' is connected to the 'H' line. It contains components labeled 1 through 2.

The diagram uses a standard electrical circuit notation with lines representing conductors and symbols for various components like resistors, capacitors, and relays.

AUTOMATIC SWITCH.

Application filed July 10, 1924. Serial No. 725,115.

This invention relates in general to automatic switches for telephone systems, and the object of the invention is the provision of a new and improved connector switch.

- 5 More specifically, the object of the invention is to provide a new and improved connector switch for semi-selective or code ringing party line systems, and according to one feature of the invention the pick-up relay 10 required in two-ring or code ringing connectors is eliminated and its functions are performed by the busy relay. According to a further feature of the invention, the slow releasing vertical and rotary series relays are 15 eliminated and their functions are performed by the switching and ringing relays, respectively. These features require the addition of rotary off-normal springs to the connector.
- 20 According to a modification of the invention a connector switch is provided in which the pick-up relay is eliminated and its functions are performed by the busy relay, without requiring the addition of rotary off-normal springs. In this modification the usual 25 vertical and rotary series relays are retained.
- The means by which the foregoing objects, together with others not specifically mentioned at this time, are accomplished will 30 be fully set forth hereinafter, reference being had to the accompanying drawings, of which Fig. 1 is a circuit diagram of the improved connector H covering the main invention, rotary line switch C, and subscribers' stations A and A'; while Fig. 2 is a circuit diagram of the improved connector H' covering the modification.
- 35 Referring to Fig. 1, the connector indicated by the reference character H is of the well known Strowger vertical and rotary type with the pick-up, vertical series, and rotary series relays eliminated and rotary off-normal springs included, and having circuits such that it is controlled over the two sides 40 of the incoming trunk in series. This connector is one of a group of two-ring connectors in a semi-selective automatic party line system. To the right of the connector H are shown the bank terminals of a subscriber's line, which extends to the substations A and A' by way of line switch C. These bank terminals are accessible to connector H and are multiplied with other similar terminals in the banks of the other two-ring connectors, and are also multiplied with 45 terminals in the banks of a group of one-ring connectors. The substations A and A' are connected in bridge of the line and are ordinary automatic telephone substations each having the usual talking and ringing 50 instrumentalities and a calling device for controlling the automatic switches. The line switch C is mechanically of the well known rotary type in which the wipers have no normal position and move in a forward 55 direction only, and is used for extending outgoing calls from substations A and A'.
- 55 Referring to Fig. 2, the connector indicated by the reference character H' is similar to connector H except that the pick-up relay only is eliminated and with the further exception that no rotary off-normal springs are required. To the right of the connector H' are shown the bank terminals of a subscriber's line (not shown), which may be 75 the party line to substation A and A' shown in Fig. 1, or another similar party line.
- 60 Some of the relays in the switches are slow to release, while some of them are slightly slow to pull up as well as release, due to a slug being placed either on the heel or on the armature end of the core. The slow to release relays are indicated on the drawings by a shaded portion on their lower or heel end, while the slow to pull up and release 65 relays are indicated by a black portion on their upper or armature end.
- 65 The apparatus, having been described more or less in general, will now be described in connection with a detailed description of its operation. For this purpose, it will be assumed that an "automatic" subscriber (not shown) desires to obtain connection with the subscriber at station A, 70 Fig. 1, which is a two-ring station. The calling subscriber's station and individual line switch are similar to A and C, respectively, and since the selector switches used by an "automatic" subscriber in completing 75 a connection are well understood by those skilled in the art and form no part of the present invention, it is believed that it will suffice to say that in response to the removal of the receiver by the calling subscriber, his individual line switch seizes an idle trunk line leading to an idle selector switch; and in response to the operation of the subscriber's calling device the selector switch is operated to select an idle trunk line leading to 80 another idle selector switch, or to select an 85

idle trunk leading to a connector switch, such as indicated by the reference character H, depending on the size of the system. Let us assume that the calling subscriber has 5 established his connection up as far as the last selector, and that the selector has come to rest on its bank contacts which are connected to the conductors 2, 3 and 4 of the connector H, this connector being the first 10 idle one in the two-ring connector group. When the selector switch comes to rest upon the contacts associated with conductors 2, 3 and 4, the switching relay of the selector completes an energizing circuit for the line 15 relay 6 of the connector switch H as follows: From ground by way of the lower winding of the line relay 6, normally closed contact controlled by armature 15, line conductor 4, over the intervening switches and 20 the subscriber's loop back to line conductor 2, normally closed contact controlled by armature 14, and through the upper winding of relay 6 to battery. Relay 6, upon energizing, closes a circuit for release relay 7 at 25 armature 16. Relay 7, upon energizing, connects ground to the release conductor 3 at armature 17, said ground completing a holding circuit for the switches back of the connector switch for maintaining said switches 30 in an operated position, and, in addition, making the trunk line to the connector H busy to all other selectors having access thereto. A further result of the energization of the relay 7 is the preparation of a 35 circuit for the vertical magnet 11 and the further opening of the release circuit at armature 19, which circuits will be explained hereinafter.

The calling subscriber may now manipulate 40 his calling device in accordance with the next to the last digit in the number of the wanted subscriber. Due to the operation of the calling device by the calling subscriber, the circuit of the line relay 6 is 45 interrupted a number of times corresponding to the digit dialled and the line relay, in response to these circuit interruptions, deenergizes during an equal number of short intervals. Relay 6, upon deenergizing, closes 50 a circuit for the vertical magnet 11 and the switching relay 10 in parallel, as follows: From ground, armature 16 and its resting contact, armature 19 and its working contact, and resting contact and vertical off-normal spring 37 to a point where the circuit divides, one branch extending by way of rotary off-normal spring 39 and its resting contact, and magnet 11 to battery; while 55 the other branch extends by way of the lower winding of relay 10 to battery. The vertical magnet 11, upon energizing, raises the wipers 50-52, inclusive, one step opposite the first level of bank contacts. Relay 10 is energized in parallel with the vertical magnet 11 and closes a locking circuit for 60 itself at armature 34 to ground at armature 16, by way of armature 19 and rotary off-normal spring 40, and being slow-acting holds up continuously during the vertical operation of the switch. By the operation 70 of this relay, the vertical magnet circuit is preserved intact, notwithstanding the shifting of the vertical off-normal springs 37 and 38, which occurs at the first vertical step of the switch. Relay 6 re-energizes, upon completion of the first interruption of the dialling circuit, and opens the circuit of the vertical magnet 11, whereupon the magnet deenergizes. This operation of the vertical magnet continues until the wipers 50-52, 75 inclusive, are raised opposite the desired level of bank contacts, the operating circuit of said magnet, after the first vertical step, being in multiple with that of relay 10 and traceable from ground, armature 16 and its resting contact, armature 19 and its working contact, resting contact and rotary off-normal springs 40, armature 34 and its working contact, rotary off-normal spring 39 and its resting contact, and magnet 11, 80 to battery. At the end of the vertical movement, relay 10 deenergizes and transfers the operating circuit to the rotary magnet 12.

The calling subscriber now transmits the final series of impulses of the called telephone number. Responsive to these interruptions the line relay 6 is deenergized a corresponding number of times and now sends impulses to the rotary magnet 12 over the following circuit: from ground, armature 16 and its resting contact, armature 19 and its working contact, working contacts controlled by vertical off-normal spring 37, resting contact and armature 33, resting contact and armature 21, and rotary magnet 12, 95 to battery. By the operation of the rotary magnet, the wipers 50-52, inclusive, are rotated step by step and are finally brought to rest in engagement with the particular set of bank contacts in which the line of substation A is terminated, the contacts being indicated in the drawing by reference characters 53, 54 and 55. The slow acting relay 9 is energized in parallel with the rotary magnet by way of armature 32 and its resting contact, and remains continuously energized during the rotary movement. In operated position relay 9 connects the test wiper 51 to the winding of the test relay 8 by means of its armature 25 and at armature 27 closes an alternative point in the circuit of the rotary magnet, to guard against the possibility of having its circuit opened by the operation of the test relay while the test wiper 51 is passing over grounded test contacts.

The final series of impulses has now been received, and the connector wipers have been placed in connection with the terminals of the called line. If the line is busy there will 130

be a ground potential on the test contact 54 and the test relay 8 will be energized. When this relay operates it prepares a locking circuit for itself at its armature 20, which is completed when the slow acting relay 9 falls back an instant later, opens the rotary magnet circuit at armature 21, and at armature 23 connects a lead from the busy signalling machine to the lower side of the line. On 10 perceiving the signal, the subscriber will replace his receiver, thereby releasing the connector H and all previously operated switches.

Assuming now that the called line is idle 15 when connection therewith is attempted, under these circumstances there will be no ground on the test contact 54, and the test relay 8 will not be energized. Then when the slow acting relay 9 falls back a circuit 20 is completed for the switching relay 10 which may be traced from the grounded conductor 3, armature 20 and its resting contact, upper winding of relay 10, resting contact and armature 25, resting contact and armature 25, test wiper 51, test contact 54, switching relay 100 of the line switch C, and magnet 102 to battery. Relays 10 and 100 are energized in series over this circuit, but due to the usual mechanical interlocking device between 25 the armature of the cut off relay 100 and the armature of line relay 101, the former is energized only half way and as a result the wipers of the called line switch C are not connected up, although line relay 101 and ground are disconnected from the called line.

In the connector H, when the switching relay 10 pulls up, it establishes a locking circuit for itself at armature 34 traceable from 30 ground, working contact and armature 18, current drain lowering resistance 45, working contact and rotary off-normal spring 40, armature 34 and its working contact, and lower winding of relay 10 to battery. Further results of the energization of relay 10 are the grounding of the test wiper 51 at armature 31, the preparation of a holding circuit for relay 9 at armature 32, the opening of the rotary magnet circuit at armature 33, and the connecting up of the two wipers 50 and 52 at armatures 29 and 36. A still further result of the energization of relay 10 is the closing of a circuit for busy relay 8 (now functioning as a pick-up relay) at armature 30 traceable from ground, wiper 42 of continuously rotating generator interrupter I, common pick-up conductor 47, working contact and rotary off-normal spring 41, armature 30 and its working contact, normally closed contact controlled by armature 20, normally closed contact controlled by armature 25, and relay 8 to battery. Relay 8, upon energizing, closes a locking circuit for itself at armature 20 by 60 way of ground at armature 17, and closes the

ringing circuit at armature 22. Armature 22 is normally closed to battery so that the ringing relay 9 will energize to break the ringing current circuit in case the called subscriber lifts his receiver between the time connection 70 is made with his line and ringing current is started; thus avoiding possible ringing in his ear. When the wiper 42 of the interrupter I passes over the segments connected with relay 43, this relay energizes and de- 75 energizes to cause two rings from the generator machine GEN. to be projected out intermittently over the called line to operate the bridged ringer at substation A to notify the called subscriber that he is wanted. The 80 ringing circuit may be traced from ground, resting contact and armature 24, armature 29 and its working contact, wiper 50, contact 53, over the called subscriber's loop and return to contact 55, wiper 52, working contact 85 and armature 36, armature 28 and its resting contact, lower winding of relay 9, armature 22 and its working contact, and armature 44 and working contact to the generator machine GEN., the calling subscriber hearing the ringing by way of the condenser 48 and working contact and armature 35.

When the called subscriber answers by lifting his receiver the ringing current bridge across the line is replaced by a direct 95 current bridge, whereupon relay 9 is operated. Upon energizing, relay 9 closes a locking circuit for itself at armature 26 traceable from ground, working contact and armature 18, armature 26 and its working contact, current drain lowering resistance 46, working contact and armature 32, and upper winding of relay 9 to battery. Further results of the energization of relay 9 are the opening of the circuit of relay 8 at armature 25, whereupon it deenergizes; breaking the ringing circuit at armatures 24 and 28; and at the working contacts of these same armatures the final completion of the talking connection. 110

Current is now supplied to the transmitter at substation A through the windings of the double wound back bridge relay 5 which is accordingly energized. This relay is a reversing relay and has the well known function of reversing the incoming trunk conductors 2 and 4 as regards their connections with the windings of the relay 6. This reversing operation is a standard operation and is for the purpose of operating subscribers' pay-stations or metering apparatus, and in some cases is used for supervisory purposes. The subscribers may now converse as desired. 115

At the end of the ensuing conversation, the 120 two subscribers replace their receivers. The replacing of the receiver at the called substation A stops current from flowing over its line and deenergizes relay 5, whereupon the conductors 2 and 4 are reversed with re- 125 130

spect to the windings of relay 6. The replacing of the receiver at the calling substation (not shown) stops current from flowing over its line and deenergizes relay 6, whereupon the circuit of the release relay 7 is broken, and a circuit for the release magnet 13 is prepared at armature 16. Relay 7, upon deenergizing, removes ground from the release trunk conductor 3 at armature 17, whereupon the preceding switches are released in the well known manner. A further result of the deenergization of relay 7 is the opening of the locking circuits of relays 9 and 10 at armature 18, allowing said relays to release, whereupon the latter relay opens the locking circuit of relay 100 at armature 31 and allows switch C to restore to normal condition. A still further result of the deenergization of relay 7 is the closing of a circuit for the release magnet 13 at armature 19, thus allowing the switch H to return to normal. The release magnet 13 is energized over the following path: from ground at armature 16 and its resting contact, armature 19 and its resting contact, vertical off normal spring 38 and its working contact, and magnet 13 to battery. The release magnet is maintained energized over the above traced circuit until the shaft and wipers are returned to their normal position, whereupon the circuit of the release magnet is opened by the separation of the vertical off normal springs.

An explanation will now be given of the operation of the system when the connector H', Fig. 2, is substituted for the connector H, Fig. 1. Let us assume that the calling subscriber has established his connection up as far as the last selector (not shown) and that the selector has come to rest on its bank contacts which are connected to the conductors 112, 113 and 114 of the connector H', this connector being the first idle one accessible to said selector. When the selector switch comes to rest upon the contacts associated with conductors 112, 113 and 114, the switching relay of the selector completes an energizing circuit for the line relay 116 of the connector switch H' as follows: from ground by way of the lower winding of line relay 116, normally closed contact controlled by armature 128, line conductor 114, over the intervening switches and the calling subscriber's loop back to line conductor 112, normally closed contact controlled by armature 127, and through the upper winding of relay 116 to battery. Relay 116, upon energizing, closes a circuit for release relay 117 at armature 129. Relay 117, upon energizing, connects ground to the release conductor 113 at armature 131, said ground completing a holding circuit for the switches back of the connector switch for maintaining said switches in an operated position, and, in addition, making

the trunk line leading to the connector H' busy to all other selectors having access thereto. Further results of the energization of relay 117 are the preparation of a locking circuit for ringing and switching relays 119 and 122 at armature 130, and the preparation of a circuit for the vertical magnet 123, and the further opening of the release circuit at armature 132, which circuits will be explained hereinafter. 75

The calling subscriber may now manipulate his calling device in accordance with the next from the last digit in the number of the wanted subscriber. Due to the operation of the calling device by the calling subscriber, the circuit of the line relay 116 is interrupted a corresponding number of times, whereupon said relay is momentarily deenergized a plurality of times and at each deenergization transmits an impulse of current to the vertical magnet 123 over a path which extends from ground by way of armature 129 and its resting contact, armature 132 and its working contact, resting contact and off normal springs 153, winding 90 of the slow to release series relay 118, and the winding of the vertical magnet 123 to battery. By the operation of the vertical magnet the wipers 170—172, inclusive, are raised step by step until they stand opposite 95 the desired level of bank contacts. Relay 118 is energized in series with the vertical magnet 123 and being slow to release holds up continuously during the vertical operation of the switch. By the operation of this 100 relay, the vertical magnet circuit is preserved intact, notwithstanding the shifting of the off-normal springs, which occurs at the first vertical step of the switch. At the end of the vertical movement, relay 118 deenergizes and transfers the operating circuit to the rotary magnet 124. 105

The calling subscriber now transmits the final series of impulses of the called telephone number. Responsive to these interruptions the line relay 116 is again deenergized a corresponding number of times and now sends impulses to the rotary magnet 124 over the following circuit: from ground by way of armature 129 and its resting contact, armature 132 and its working contact, resting contact and normally open contact controlled by off normal spring 153, armature 133 and its resting contact, resting contact and armature 141, resting contact and armature 150, and the winding of the rotary magnet 124 to battery. By the operation of the rotary magnet, the wipers 170—172, inclusive, are rotated step by step 115 and are finally brought to rest in engagement with the particular set of bank contacts in which the line of the wanted subscriber is terminated, these contacts being indicated in the drawing by reference characters 173, 174 and 175. The slow to re- 120

lease relay 121 is energized in parallel with the rotary magnet and remains continuously energized during the rotary movement. In operated position, relay 121 connects the 5 test wiper 171 to the winding of the test relay 120 by means of its armature 143, and at armature 144 closes an alternative point in the circuit of the rotary magnet to guard against the possibility of having this circuit opened by the operation of the test relay while the test wiper 171 is passing over grounded test contacts.

The final series of impulses has now been received, and the connector wipers have 15 been placed in connection with the terminals of the called line. If the line is busy there will be a ground potential on the test contact 174 and the test relay 120 will be energized. When this relay operates it prepares a locking circuit for itself at its armature 138, which is completed when the slow to release relay 121 falls back an instant later; opens the rotary magnet circuit at armature 141, and at armature 142 connects a lead from the busy signalling machine to the lower side of the line. On 20 perceiving the signal, the subscriber will replace his receiver, thereby releasing the connector H¹ and all previously operated 25 switches in the usual well known manner.

Assuming now that the called line is idle when connection therewith is attempted, under these circumstances there will be no ground on the test contact 174, and the test 30 relay 120 will not be energized. Then when the slow to release relay 121 falls back a circuit is completed for the switching relay 122 which may be traced from ground by way of armature 131 and its working contact, armature 138 and its resting contact, lower winding of the switching relay 122, resting contact and armature 143, test wiper 171, test contact 174, and winding of the 35 cut-off or switching relay of the line switch (not shown) to battery. Relay 122 and the cut off relay of the line switch are energized in series over this circuit, and the latter relay operates to clear the line conductors of their normal battery and ground 40 connections in the line switch.

At the connector H¹, when the twitching relay 122 pulls up it establishes a locking circuit for itself at armature 148, grounds the test wiper 171 at armature 147, opens 45 the rotary magnet circuit at armature 150, connects up the two line wipers 170 and 172 at armatures 145 and 152, and at armature 149 prepares a circuit for busy relay 120 (now functioning as a pick-up relay) which may 50 be traced as follows: from ground by way of wiper 155 of the continuously rotating generator interrupter I¹, common pick-up conductor 158, normally closed contact controlled by armature 140, resting contact and 55 armature 136, working contact and armature 149, and winding of relay 120 to battery. Relay 120, upon energizing, closes a locking circuit for itself at armature 140 by way of ground at armature 131, and closes the ringing circuit at armature 139. Armature 139 is normally closed to battery so that the ringing relay 119 will energize to break the ringing current circuit in case the called subscriber lifts the receiver between the time connection is made with his line and ringing current is started; thus avoiding possible ringing in his ear. When the wiper 155 of the interrupter I¹ passes over the segments connected with the interrupter relay 156, this relay energizes and deenergizes to cause two 60 rings from the generator machine GEN. to be projected out intermittently over the called line to operate the bridged ringer at the called substation to notify the subscriber that he is wanted. The ringing circuit 65 may be traced from ground by way of armature 137 and its resting contact, armature 152 and its working contact, wiper 172, bank contact 175, through the ringer and condenser at the called substation (not 70 shown) and back to the bank contact 173, wiper 170, working contact and armature 145, armature 134 and its resting contact, lower winding of the ring cut-off relay 119, armature 129 and its working contact, and 75 armature 157 and its working contact to the generator machine GEN. Relay 119 being marginal will not operate in series with the ringer and condenser at the called substation. The ringing of the called subscriber's bell continues intermittently until he answers by removing his receiver from the switchhook, or the calling subscriber 80 abandons the call and restores his receiver, the calling subscriber receiving the usual 85 well known ringing tone by way of armature 146 and condenser 159, as long as the ringing continues and he holds the receiver to his ear.

When the called subscriber answers, a 90 direct current bridge is closed across the conductors of the line, thereby operating relay 119. This circuit may be traced over the same path as for the ringing current, except for the direct current bridge at the 95 substation, up to and including armature 157 where it continues by way of its resting contact to battery, in case the receiver is removed during the silent period, or through the generator to battery if the receiver is 100 removed during a ringing period. Upon energizing, relay 119 closes a locking circuit for itself at armature 135 by way of ground at armature 130 and its working contact; opens the locking circuit of relay 120 at 105 armature 136, whereupon said relay de-energizes and restores its armatures to normal condition; and at armatures 134 and 137 disconnects the wipers 170 and 172 from its own lower winding and ground, respec- 110

- tively, and extends them to the windings of the back bridge relay 115. Relay 115 is operated and reverses the battery to the calling party, so that a meter or coin collector 5 can be operated at the calling station, if desired. The calling and called subscribers may now converse with each other as desired, the talking circuit being outlined by the heavy conductors.
- 10 At the end of the ensuing conversation, the two subscribers replace their receivers. The replacing of the receiver at the called substation stops current from flowing over its line and deenergizes relay 115.
- 15 When the receiver is replaced at the calling substation, the circuit of the line relay 116 is opened and it deenergizes. Upon armature 129 being retracted the circuit of release relay 117 is opened, while a circuit 20 is prepared for the release magnet 125. Relay 117, upon deenergizing, disconnects ground from the release trunk conductor 113 at armature 131, whereupon the preceding switches are restored to normal condition.
- 25 A further result of the deenergization of relay 117 is the opening of the locking circuits of relays 119 and 122 at armature 130, whereupon said relays deenergize and restore their armatures to normal condition.
- 30 A still further result of the deenergization of relay 117 is the closing of a circuit for release magnet 125 at armature 132 by way of off normal spring 154 and its working contact, whereupon said magnet operates to 35 restore the wipers of the connector H' to normal position. When the wipers reach their normal position the circuit of release magnet 125 is again opened at off normal spring 154 by the switch shaft in the usual 40 well known manner.
- The invention having been fully described, what is considered new and is desired to have protected by Letters Patent will be pointed out in the appended claims.
- 45 What is claimed is:
1. In a telephone system, a connector switch, wipers for said switch, a vertical magnet in said switch for stepping said wipers vertically, a switching relay in said 50 switch, circuit means for operating said switching relay in parallel with said vertical magnet, means whereby said switching relay is made slow acting so that it is held operated during the vertical stepping of said wipers to maintain the operating 55 circuit of said magnet intact, a rotary magnet for stepping said wipers to a called line, and contacts on said switching relay for closing the ringing circuit to said wipers 60 when the called line is connected with.
  2. In a telephone system, a connector switch, wipers for said switch, a vertical magnet in said switch for stepping said wipers vertically, a switching relay in said 65 switch, circuit means for operating said
- switching relay in parallel with said vertical magnet, means whereby said relay is made slow acting so that it is held operated during the vertical stepping of said wipers to maintain the operating circuit of said vertical magnet intact, said switching relay being released upon completion of the vertical stepping thereby breaking the operating circuit of said vertical magnet, a rotary magnet 70 for stepping said wipers to a called line, and contacts on said switching relay for closing the ringing circuit to said wipers when the called line is connected with.
3. In a telephone system, a connector switch, wipers for said switch, a rotary 80 magnet in said switch, a ring cut off relay in said switch, a circuit for operating said ring cut off relay in parallel with said rotary magnet, means for intermittently closing said circuit to cause said magnet to rotate 85 said wipers, and means whereby said ring cut off relay is made slow acting so that it is held operated during the rotary motion of said wipers to maintain the operating circuit of said magnet intact.
4. In a telephone system, a connector switch, test and line wipers for said switch, a rotary magnet in said switch for rotating said wipers horizontally, a ring cut off relay in said switch, circuit means for operating said ring cut off relay in parallel with said rotary magnet, means whereby said ring cut off relay is made slow acting so that it is held operated during the horizontal stepping of said wipers to maintain the operating 95 circuit of said rotary magnet intact and is released upon completion of the horizontal stepping, a test relay in said switch, and a circuit controlled by said ring cut off relay for energizing said test relay before said ring cut off relay deenergizes if said test wiper finds ground at the end of its horizontal stepping.
5. In a telephone system, a connector switch, test and line wipers for said switch, a rotary magnet in said switch for rotating said wipers horizontally, a ring cut off relay in said switch, circuit means for operating said ring cut off relay in parallel with said rotary magnet, means whereby said ring 100 cut off relay is made slow acting so that it is held operated during the horizontal stepping of said wipers to maintain the operating circuit of said rotary magnet intact, a switching relay in said switch, and means 110 whereby said switching relay is operated responsive to the deenergization of said ring cut off relay if said test wiper finds battery at the end of its horizontal stepping.
6. The combination, with an automatic 115 vertical and rotary switch for connecting with a line, of a combination vertical control and switching relay, said relay having normally open contacts for maintaining the operating circuit of the vertical magnet intact during 120
- 125
- 130

- the vertical movement and for connecting up the switch wipers upon being connected with an idle line, and vertical and rotary off normal springs for controlling the said relay.
- 5 7. The combination, with an automatic vertical and rotary switch for connecting with a line, of a combination rotary control and ring cut off relay, said relay having normally open contacts for maintaining the 10 operating circuit of the rotary magnet intact during the rotary movements and having contacts for opening the ringing circuit when the receiver is removed at the called substation.
- 15 8. The combination, with an automatic code ringing switch for connection with a party line and signalling a station on said line, of a combination busy test and pick up relay means for energizing said relay when 20 the switch connects with a busy line and contacts on said relay for completing the code ringing circuit at the proper time so as not to mutilate same when the switch connects with an idle line.
- 25 9. A connector switch having primary and secondary movements, means for changing over from primary to secondary movement, means for connecting the switch wipers when the secondary movement is completed, 30 and a single magnet for controlling said change-over means and said connecting means, said magnet controlling the primary movement when energized and the secondary movement when deenergized.
- 35 10. In a connector switch, a test relay, a switching relay, a test wiper, contacts for connecting said wiper to either of said relays, a ringing circuit, contacts for breaking said ringing circuit when a called party 40 answers, and a single relay for operating all said contacts.
11. In a connector switch, a test relay, a test wiper, contacts for connecting said wiper with said relay while the switch is being operated to connect with a line and for 45 breaking the connection after the line is connected with, a ringing circuit, contacts for breaking said ringing circuit when the
- called party answers, and a single relay for operating all said contacts. 50
12. In a two motion connector switch, a combination secondary control and ring cut off relay, means for maintaining said relay energized during the secondary movement of said switch to control the test circuit 55 thereof, said relay being deenergized when the secondary movement is completed, a ringing circuit for signalling the called line, and means for energizing said relay to break said ringing circuit when the called party 60 answers.
13. In a connector switch, a combined test and pick-up relay, means for energizing said relay to signal the calling line if the called line is busy when connected with, 65 means for preparing a code ringing circuit if the called line is idle, and means for energizing said relay to complete said ringing circuit.
14. In a telephone system, a connector 70 switch, test and line wipers for said switch, a rotary magnet in said switch for rotating said wipers horizontally to select a line, a ring cut-off relay in said switch, circuit means for operating said ring cut-off relay 75 in parallel with said rotary magnet, means whereby said relay is made slow acting so that it is held operated during the horizontal stepping of said wipers to maintain the operating circuit of said rotary magnet intact, a switching relay in said switch, and means whereby said switching relay is operated responsive to the deenergization of said ring cut-off relay if said test wiper finds the selected line to be idle. 80
15. In a connector switch, a combination busy test and ringing circuit control relay, contacts on said relay for closing a busy signalling circuit when the connector connects with a busy line, and contacts on said relay for closing the ringing circuit when said connector connects with an idle line. 90

In witness whereof, I hereunto subscribe my name this fifth day of July, A. D., 1924.

HANS P. BOSWAU.
